ROLL TYPE MERCURY SWITCH

Edward R. Coutant, Stratford, Conn., assignor
to General Electric Company, a corporation of
New York

Application March 29, 1952, Serial No. 279,294

5 Claims. (Cl. 200—152)

1

This invention relates to electric switches and in particular to a new roll type mercury button switch.

By mercury button switch is meant that type of electrical switching device containing a mercury button rotatable to an "on" or "off" position. Conventionally a mercury button comprises, a pair of metallic shells separated by an insulating barrier having a passageway therein. When the metal shells and barrier are rotated to a predetermined position, mercury stored between each shell and the barrier passes through the passageway in the barrier to establish electrical contact between the shells and thereby act as a switching device.

In mercury button switching devices of a usual type, the mercury button is nested in a yoke having an operating finger extending through an aperture in the switch face plate. The finger is movable to rotate the button to an "on" and "off" position where it is held by a detent arrangement.

In these switches, electrical contact for connecting the switch in an electrical circuit is made generally between the button shells and external pressure contacts at the side of the metal shell with the pressure contacts being located approximately at the geometric axis of rotation of the shell. Such a contact arrangement within a switch of normal household size limits the spring pressure that can be used, the area of contact, and hence the load carrying capacity of the switch.

One of the objectives in the switch art is to increase the load carrying capacity of mercury button switches, and one approach to this end is to increase the area of contact and the contact pressure between the button shells and external pressure contacts for a mercury button.

It is an object of this invention therefore to provide a mercury button switch having an improved contact arrangement, for engaging the mercury button thereby to increase its load carrying capacity.

It is a further object of this invention to provide a mercury button switch having roll type trigger and improved contact arrangement.

It is a further object of this invention to provide an improved mercury button switch having an integral housing and face plate.

It is a still further object of this invention to provide a mercury switch having an integral housing and face plate in combination with an improved roll type trigger and an improved contact arrangement.

2

Further objects and advantages of this invention will become apparent and the invention will be more clearly understood from the following description, referring to the accompanying drawing, and the features of novelty which characterize this invention will be pointed out with particularity in the claims annexed to and forming a part of this specification.

In the drawings, Fig. 1 is a rear elevation of a three-way mercury button switch having an integral face plate; Fig. 2 is a side elevation in section taken along the line 2—2 of Fig. 1; Fig. 3 is a top view partly in section taken along the line 3—3 of Fig. 2; Fig. 4 is a front elevation (reduced scale) of the combination face plate and roll type switch shown in Fig. 1; Fig. 5 is an exploded perspective view of the combination face plate and switch shown in Fig. 1; Fig. 6 is rear elevation of a second embodiment of this invention wherein the face plate and the switch are separable; Fig. 7 is a side elevation partly in section taken through the plane 7—7 of Fig. 6; Fig. 8 is a top view partly in section along the line 8—8 of Fig. 7; Fig. 9 is a front elevation (reduced in scale) of the switch shown in Fig. 6; while Fig. 10 is an exploded perspective view (enlarged scale) of the switch shown in Figs. 6—9. It is to be noted that these figures are not all to the same scale, but they have been enlarged or contracted as deemed necessary to point out as clearly as possible the operating principles and features of this invention.

Briefly this invention comprises an arrangement involving the nesting of a mercury button in a roll type switch arm and the use of bottom contacts for engaging the peripheral surface of the button shells. Furthermore, this invention provides an integral face plate and switch combination for use with a mercury button having roll type action and improved bottom contacts.

Referring to Figs. 1—5 of the drawings, the integral face plate and switch 1 is shown as comprising a body member 2, a pair of mercury buttons 3, 4 and spring contacts 5, 6, 7, each having terminal screws 8, 9, 10 respectively.

The particular embodiment shown in Figs. 1—5 is a three-way switch having two mercury buttons and three spring contacts. It is to be understood, however, that this particular embodiment is used merely as an example to illustrate more clearly the operating principles and features of this invention and that it is not so depicted as a limitation on the scope of this invention.

The body 2 may be made from one of the phenolic or urea resins or any other suitable insu-

lating material approved for such use, and it is shaped to form a face plate 11 integral with switch housing 12. The switch housing is shaped to fit into an outlet box of conventional form and the face plate 11 is provided with suitable bores 13 for accommodating mounting screws for positioning the combination face plate and switch on an outlet or switch box.

The mercury buttons 3, 4 are of a conventional type as described, for example, in U. S. Patent 2,101,092 assigned to the same assignee as that of the present invention; but briefly each mercury button comprises (see Fig. 5) a pair of shells 14 and 15 made of some electrical conducting material, a glass ring 16 to form a seal while insulating the shells from one another, and a ceramic barrier (not shown) within the shells. The barrier has a passageway therein parallel to the geometric axis of rotation of the buttons and a pool of mercury is stored between each of the shells and the barrier so that when the barrier is rotated to a predetermined position, the mercury enters the passageway and establishes electrical contact between the shell.

The spring contacts 5, 6 and 7 are a fundamental element of this invention in that they present something new in the mercury button art. Specifically, the contacts or elements 5, 6 and 7 are made of any resilient electrical conducting material and they are constructed to establish an external pressure contact respectively between the peripheries of shells 14 and 15 of each mercury button and an external electric circuit. For example, in the illustrated embodiment (Figs. 1 and 3) the strip 5 contacts the shell 14 of mercury button 3, the strip 6 contacts both the shell 15 of the mercury button 3 and the shell 15 of mercury button 4, while strip 7 contacts the shell 14 of mercury button 4.

The mercury buttons are inversely arranged so that when they are rotated to one position, electrical contact is established between two of the strips, for example strips 5 and 6, and broken between the other two strips, for example strips 6 and 7. When rotated to a second position, contact is broken between the strips 5, 6 and established between strips 6, 7. For either switching action, the mercury runs out of the passageways in the barrier in one of the buttons and into the passageway of the barrier in the second button.

Each of the contacts 5, 6 and 7 as shown more particularly in Fig. 5 is made from resilient electrical conducting material, for example, Phosphor bronze, and formed to have a binding screw plate 17 or other wire connecting means at one end and a curved pressure contacting portion or bow 18 approximately midway of its length to engage the peripheral rim of one of the shells of the mercury buttons.

The housing portion 12 of the switch is slotted to accommodate the binding screw plate 17. For example, nests 19, 20 and 21 are slotted into the housing 12 to accommodate the binding screw plate 17 of the strips 5, 6 and 7 respectively. The housing is further provided with recesses as at 22 to receive the free end of the center contacts 6, thereby to provide a sturdy support for the contact to assure the pressure engagement with the peripheries of shells 15 of the adjacent buttons 3, 4. Shoulders 23 and 23a are also provided for the free ends of strips 7 and 5 respectively. With this structure both ends of each of the spring strips 5, 6 and 7 are supported

to afford a pressure contact between the strips and the mercury buttons.

A trigger 24 of insulating material is provided for the operation of the mercury button switch. The trigger is substantially semi-cylindrical and hollowed out at its center to provide clearance grooves 25, 26 to accommodate the glass seals 16 of the buttons 3 and 4 respectively. The trigger, in turn, is provided at each end with flange-like shoulders 27 having a stop 28 positioned thereon. A boss 29 complementary to shoulders 27 is positioned on each side of the housing 12 to support the shoulders and thereby guide the rotation of trigger 24. To limit the rotation of trigger 24, a slot 30 is notched in bosses 29 to provide limits for engaging the stop 28 to control the rotation of trigger 24.

After the trigger 24 has been assembled into the switch housing with the buttons 3, 4 resting in the clearance grooves 25, 26, then the spring contacts 5, 6, 7 are positioned to overlie the respective shells while the binding screw plates 17 are positioned in their respective nests 19, 20 and 21, whereupon a back plate 31, made of any suitable insulating material, is attached to the back of the housing 12 and fastened in place by means of the screws 32.

The back plate 31 thus presses the free ends of the contact strips down upon the respective abutments 23, 22, and 23a tensioning the bowed portions 18 of the several contact strips against the peripheral contact surfaces of the buttons. Thus, not only is a large contact surface area established, but also each contact is maintained under greater spring pressure than has been possible with prior art constructions. It will also be noted that in assembly of the switch, the contact strips, being the last elements to be placed in the housing, are never deformed away from the buttons and hence the contact pressure is uniform for all switches, thereby giving assurance that the contact pressure in the manufactured article will be of the value intended by the designer.

With this structure, it can be seen that the assembled switch may be installed in an outlet box with simplicity; that is, the binding screws 8, 9, 10 are at the top and bottom of housing 12 where they are easily accessible for wiring, and the housing 12 and face plate 11 may be installed in one operation by passing screws through bores 13 in the face plate to engage an outlet box.

The front view shown in Fig. 4 illustrates a button or finger rest 33 in the rotary trigger 24 to facilitate its operation. In one embodiment of this invention, luminous material such as a luminous tape may be placed over the outer periphery of the button so that the switch can be seen in the dark. Of course, some plastic surface coating might be put over the luminous material to protect it.

The embodiment as shown in Figs. 6 through 10 is substantially similar to that shown in Figs. 1 to 5 with the exception that in Figs. 6 through 10, a single pole switch is shown and the construction uses a separable face plate.

In the embodiment illustrated in Figs. 6 through 10, a housing 36 is provided with face plate 37 and a backing plate 38. A rotary trigger 39 similar to that shown as 24 in Fig. 5, is provided with a hollow center for receiving a mercury button 3; that is, the center of the rotary trigger 39 is hollowed out and bearing-like receptacles 40 are provided at each inner axial end 75 to accommodate the button shells 14 and 15

while a suitable stop (not shown) is provided within the rotary trigger 39 to prevent relative movement between the trigger and the button when the two have been assembled. The housing 36, like the housing 12, is provided with a bearing-like support or protrusion 41 for accommodating complementary flange-like members 42 extending from either axial end of the rotary trigger 39. The flange-like members 42 have a stop 43 adapted to move within the limits of a gap 44 in protrusions 41 to limit the rotation of the trigger 39. The length of the gap is defined by shoulders 45, 46 which are engageable with stop 43.

To assemble the switch, mercury button 3 is inserted into the hollow rotary trigger 39 which, in turn, is placed into the housing 36 with the stop 43 extending through the slot 44. Then spring contacts 47 and 48 which are similar to the spring contacts 5, 6 are inserted so that their binding screw plates 49, 50 slide into registering nests 51 and 52 respectively in housing 36. To provide for the interengagement between the spring contacts 47, 48, and button shells 14, 15, the spring contacts are bowed, as at 53, to conform to the periphery of the shells 14 and 15.

It should be noted in this instance that the strips 47, 48 in addition to being supported at one end by the nests 51 and 52 are supported at their opposite ends by shoulders 54, 55 respectively so that the bow 53 is suspended for bias toward the shells 14, 15.

The backing plate 38 is provided with a barrel-like bulge 56 which conforms with the contour of button 3. When backing plate 38 is inserted in place and secured by screws 57, it presses springing contacts 47, 48 into engagement with shells 14, 15 of button 3 and holds the other elements of the button in assembled relationship.

Thus, as in the preceding modifications, with both ends of the spring contacts supported and with the back plate holding the spring contact ends in position, the bowed portions of the contacts will bear firmly against the button contact shell surfaces so that a desired degree of contact pressure can be achieved and maintained. Also, because of the construction permitting assembly of a device from the back, no undesirable deformation of the contact strips will occur during assembly.

Housing 36, like conventional switches, is provided with a mounting bracket 58 having clearance bores 59 through which screws 60 may pass to secure the mounting bracket 58 and switch housing 36 to a switch box 61. After the switch has been mounted in the box, a cover or face plate 37 may be attached to the bracket 58 and hence to the switch by means of some suitable screws 62.

It will be evident that the single pole switch arrangement of Figs. 6-10 may be used in the integral housing and face plate construction of Figs. 1-5, and conversely that the three-way switch of Figs. 1-5 may be constructed to have a separable face plate as in Figs. 6-10. Other modifications of this invention will occur to those skilled in the art and it is desired to be understood, therefore, that this invention is not to be limited to the particular embodiments disclosed but rather is it intended to cover all modifications which are within the true spirit and scope of this invention.

What I claim as new and desire to secure by Letters Patent of the United States is:

1. A mercury switch comprising an integral face plate and body member made of insulating material, a rotary trigger for operating the switch, a mercury button having a pair of cup-shaped shell terminals separated by an insulating barrier, means adapting said rotary trigger to house said mercury button while permitting portions of the peripheral wall of said mercury button shells to be exposed, means rotatably supporting said rotary trigger in said housing, said trigger supporting means including bushing-like projections on each end of said trigger and complementary bearing surfaces in said housing for engaging said trigger projections, stop means positioned on said trigger to be engageable with predetermined shoulders in said housing for limiting the rotation of said rotary trigger with respect to said housing, elongated strip spring contact means for engaging the peripheral surface of said buttons, means securing one end of said spring contact means in said housing, abutment means supporting the opposite end of each of said spring contact means, a bow in the center of each of said spring contact means for engaging the peripheral surfaces of said mercury contact buttons and a back cover for said housing to hold the parts in assembled relationship, and said cover when assembled being positioned to press against said one end of each spring contact means for causing the latter to exert spring pressure against the button surfaces.
2. A three-way mercury switch comprising a housing made of insulating material, a rotary trigger made of insulating material, a pair of mercury buttons, said trigger having means for supporting said mercury buttons in juxtaposition, each of said buttons having a pair of cup-shaped shells forming switch terminals, separate spring contact strips for engaging the outer shells of each of said buttons, spring contact strips for engaging adjacent shells of said buttons, terminal means positioned at one end of each of said strips for connecting the same in an electrical circuit, said trigger having bushings extending axially from each end, said housing having bearing-like supports for engaging said trigger bushings, cooperating stop means on said trigger and housing for limiting the rotation of said rotary trigger in said housing, said spring contact strips each having a bowed portion centrally thereof shaped to engage the peripheral surfaces of said mercury buttons, means securing one end of said contact strips to said housing, a backing plate made of insulating material for closing said housing and for holding said switch elements in assembled relationship and said cover when assembled being positioned to press against the free end of each of said contact strips for causing the latter to exert spring pressure against the button surfaces.
3. A mercury button switch comprising a hollow insulating casing having a front opening and an open back, a hollow trigger element journaled for limited rotation in said casing and having a portion accessible through said front opening, a mercury button switch element disposed within said trigger element for rotation therewith and having a pair of contact shells with cylindrical surfaces separated by an apertured insulating barrier, an elongated spring contact strip having an intermediate portion adapted to engage a peripheral contact surface of said switch element, means securing one end of said strip to said casing, an abutment in said casing adapted to

support the free end of said strip, and a back cover for said housing adapted to press the free end of said strip against said abutment and thereby to urge said intermediate portion into pressure contact with said switch element surface.

4. A mercury button switch comprising a hollow insulating casing having a front opening and an open back, a hollow trigger element journaled for limited rotation in said casing and having a portion accessible through said front opening, a pair of mercury button switch elements disposed side by side within said trigger element for rotation therewith and each having a pair of contact shells with cylindrical surfaces separated by an apertured insulating barrier, a plurality of elongated spring contact strips having intermediate portions adapted to engage the peripheral contact surfaces of said switch elements, means securing one end of each of said strips to said casing, abutments in said casing adapted to support the free ends of said strips and a back cover for said housing adapted to press the free ends of said strips against said abutments and thereby to urge said intermediate portions into pressure contact with said switch element surfaces.

5. A mercury button switch comprising a hollow insulating casing having a front opening

and an open back, a hollow trigger element journaled for limited rotation in said casing and having a portion accessible through said front wall aperture, a mercury button switch element disposed within said trigger element for rotation therewith and having a pair of contact shells with cylindrical surfaces separated by an insulating barrier, elongated spring contact strips having intermediate bowed portions shaped to conform to the peripheral contact surfaces of said switch element, means securing one end of each of said strips to said casing, abutments in said casing adapted to support the free ends of said strips, and a back cover for said housing adapted to press the free ends of said strips against said abutments and thereby to urge said bowed portions into pressure contact with said switch element surfaces.
